UNITED STATES PATENT OFFICE.

ERNEST A. HAMILTON, OF PHILADELPHIA, AND FRANK W. CALVERT, OF NARBERTH, PENNSYLVANIA, ASSIGNEES TO SCOTT PAPER COMPANY, OF PHILADELPHIA, PENNSYLVANIA, A CORPORATION OF PENNSYLVANIA.

DISPENSING MEANS FOR PAPER FOR TOILET OR TOWEL PURPOSES.

1,141,541.

Specification of Letters Patent.

Patented June 1, 1915.

Application filed May 16, 1914. Serial No. 838,905.

To all whom it may concern:

Be it known that we, ERNEST A. HAMILTON and FRANK W. CALVERT, citizens of the United States, and residents, respectively, 5 of Philadelphia, county of Philadelphia, and State of Pennsylvania, and Narberth, Montgomery county, State of Pennsylvania, have invented an Improvement in Dispensing Means for Paper for Toilet or Towel 10 Purposes, of which the following is a specification.

Our invention has reference to a new and useful improvement in dispensing means for paper for toilet or towel purposes, and consists of certain improvements which are 15 fully set forth in the following specification and shown in the accompanying drawings forming a part thereof.

Our invention has for an object to provide 20 a paper package and cabinet therefor, the one coöperating with the other in such a manner that the sheets of paper are not only maintained accurately disposed and uniform as a package, but are so held that the lower- 25 most sheet of the package automatically assumes a position whereby it may be readily grasped and removed from the cabinet without affecting or destroying the relation between the remaining sheets.

It has for a further object to provide a 30 cabinet having a discharge opening formed by spacing ledges or supports for the paper package, each of which supports bears a definite relation to the package and maintains the latter effectively positioned to 35 carry out the desired discharging operation.

Our invention also comprehends details of 40 construction which, together with the features above specified, will be better understood by reference to the drawings, in which:

Figure 1 represents a front elevation showing a cabinet embodying our invention, the door of the cabinet being partially 45 broken away to disclose the interior; Fig. 2 represents a section on line $x-x$ of Fig. 1; Fig. 3 represents a section on line $y-y$ of Fig. 1; and Fig. 4 represents a development of one of the sheets of paper.

1 designates a suitable cabinet for containing and coöperating with a package of paper, the sheets of which are adapted to be delivered singly and successively, and wherein the removal of the bottom sheet

causes the next succeeding sheet to automatically move into position where it in turn may be readily grasped and withdrawn. The cabinet 1 is preferably provided with a door 2 which forms one side thereof and when open permits the package 55 of paper to be easily located within the cabinet and operatively positioned for the removal of the sheets. At suitable points within the cabinet guide plates 3 are provided to insure the package being maintained properly alined within the cabinet but out of contact with the sides thereof in order to minimize friction. 65

4 designates a plate of transparent material here shown as carried by the door 2, the latter being apertured as shown at 5 so that the condition and supply of the package within the cabinet may be observed at any time. 70

6 designates a shelf formed at the lower 75 end of the cabinet, preferably by bending the material of the casing and reversely turning the outer edge to form a rounded or cylindrical portion 7 to provide a smooth surface over which the sheets of paper may 80 be readily drawn. It will be noted that the shelf 6 is upwardly disposed at an angle to the side of the cabinet and terminates adjacent the end of one of the tab portions of the folded sheets, this latter being more particularly described hereinafter. The portion 7 of the shelf 6 extends transversely of the cabinet from one side to the other and corresponds in length substantially to the length of the paper package, while opposite 85 to this rounded edge there is a ledge 8 formed also by reversely bending the material of the casing. This ledge 8 also extends the length of the cabinet, thus forming with the edge 7^a the discharge outlet 9. The 90 width of the ledge 8 is comparatively much less than the width of the shelf 6, and serves to support the side of the package opposite to the shelf 6. The function of thus arranging the supporting shelf 6 and ledge 8 will 95 be seen by referring to the manner in which the package is built up or assembled. 100

In Fig. 4 is shown one of the sheets of the package folded in accordance with our invention and wherein 10 designates a median fold of the sheet whereby a double ply thickness of the sheet is provided. After folding the sheet along this median line the 105

side edges are again folded as shown at 11 and 12 to form tabs 13 and 14, the former in the assembled package being at one side of the package while the other is at the opposite side. By reference to Fig. 2 it will be seen that the tabs of each sheet are both preferably folded to the same side of the body of the sheet, and therefore when the successive sheets are placed in superposed relation a package of uniform appearance will be the result. When the package with the sheets so folded is placed within the cabinet, the shelf 6, for example, will support the folded tab 14 throughout substantially its entire length while the ledge 8 will serve to prevent the side of the package having the tabs 13 from dropping through the discharge opening 9. The ledge 8, however, is designedly of such a width as to allow the greater portion of the length of the tab 13, considered transverse to the fold, to remain unsupported, and therefore this tab normally assumes the hanging or depending position shown in Fig. 2 whereby it partially projects through the opening 9. Thus, while one side of the package is supported in such a manner that it has a tendency to throw the lowermost sheet partially through the opening 9, the opposite side of the package is maintained in fixed position by the inclined shelf 6 so that the weight of the package is thrown toward the side or rear of the cabinet rather than toward the opening 9. This is an important feature of construction since one sheet may be readily withdrawn at a time without causing the entire package to sag intermediate the supports and fall or be inopportune discharged through the opening 9. Furthermore, it will be noted that the width of the discharge opening 9 is preferably of a width greater than the width of the unsupported or free end of the tab 13, since thereby the tab 13 of each sheet, when it becomes the bottom sheet, unfolds automatically or drops by gravity so as to project through the opening.

It will now be apparent that we have devised a novel and useful construction which embodies the features of advantage enumerated as desirable, and while we have in the present instance shown and described the preferred embodiment thereof which has been found in practice to give satisfactory and reliable results, it is to be understood that we do not restrict ourselves to the details, as the same are susceptible of modification in various particulars without departing from the spirit or scope of the invention.

Having thus described our invention,

what we claim and desire to protect by Letters Patent is:—

1. In a device of the character stated, a cabinet providing a chamber adapted to contain a plurality of sheets of paper arranged in superposed relation and each sheet folded to form a tab which is independent and out of contact with the tab of other sheets, said chamber having a wide opening at the bottom thereof for delivering the said sheets, a narrow ledge bounding one side of said opening for supporting one side of the assembled sheets but leaving the tab free to project through said opening, a wide shelf bounding the opposite side of said opening for supporting the other side of said sheets, said shelf being inclined upwardly toward said opening to direct the weight of one side of the assembled sheets away from said opening and having its inner edge above the inner edge of said narrow ledge whereby said sheets are maintained in operative relation with the tab of the bottom sheet free to depend through said opening by its weight.

2. In a device of the character stated, a cabinet providing a chamber adapted to contain a plurality of sheets of paper arranged in superposed relation and each sheet folded to form a tab which is independent of and out of contact with the tabs of other sheets, said chamber having an opening at the bottom thereof for delivering the said sheets, a narrow ledge bounding one side of said opening and inclined downwardly toward and bounding one side of said opening for supporting one side of the assembled sheets but leaving the tab of the bottom sheet free to fall and project itself through said opening, a wide shelf spaced from said ledge and bounding the opposite side of said opening for supporting the other side of the sheets, said shelf inclined upwardly toward said opening and having its upper transverse edge lying in a horizontal plane above and parallel to the upper part of said ledge, whereby the body of said sheets are supported approximately at the middle and sag down at the ends and positively supported upon the wide shelf while leaving the other ends lightly supported upon the ledge with the lowermost tab free to fall through the opening.

In testimony of which invention, we hereunto set our hands.

ERNEST A. HAMILTON.
FRANK W. CALVERT.
